TAMPON INSERTER

Evelyn Ciencewicki, South River, N.J., assignor to
Personal Products Company, Milltown, N.J.

Filed Sept. 10, 1973, Ser. No. 395,474

Term of patent 14 years

Int. Cl. D24—02

U.S. Cl. D83—12 A

FIG. 1 is a perspective view of a tampon inserter of my new design;

FIG. 2 is a top plan view of said tampon inserter;

FIG. 3 is a side elevational view of said tampon inserter;

FIG. 4 is a left end view of the tampon inserter as shown in FIG. 3;

FIG. 5 is a right end view of the tampon inserter as shown in FIG. 3; and

FIG. 6 is a cross-sectional view of the tampon inserter shown in FIG. 3 and taken along line 6—6.

I claim:

The ornamental design for a tampon inserter, as shown and described.
